UNITED STATES PATENT OFFICE.

WILLIAM S. CROSBY, OF MANITOU, COLORADO.

DESIGN FOR A JAR.

Application filed August 24, 1925. Serial No. 14,580. Term of patent 7 years.

To all whom it may concern:

Be it known that I, WILLIAM S. CROSBY, a citizen of the United States, residing at Manitou, in the county of El Paso and State of Colorado, have invented a new, original, and ornamental Design for a Jar, of which the following is a specification, reference being had to the accompanying drawing, forming part thereof.

I claim:—

The ornamental design for a jar, as shown.

WILLIAM S. CROSBY.
